UNITED STATES PATENT OFFICE.

FRANK H. HOBERG, OF GREEN BAY, WISCONSIN.

PROCESS OF WAXING PAPER.

1,167,403.

Specification of Letters Patent. Patented Jan. 11, 1916.

Application filed January 6, 1913. Serial No. 740,367.

To all whom it may concern:

Be it known that I, FRANK H. HOBERG, a citizen of the United States, residing at Green Bay, county of Brown, and State of Wisconsin, have invented new and useful 5 Improvements in Processes of Waxing Paper, of which the following is a specification.

My invention relates to improvements in 10 processes of waxing paper. The general practice heretofore has been to discharge melted wax through a perforated cylinder upon the paper after the process of manufacturing the paper has been completed. 15 This has resulted in an unequal distribution of the wax, it being necessary to wind the paper upon a roll immediately after such a waxing operation and it has been found to frequently adhere to the superposed paper 20 in the roll, whereby it becomes virtually impossible to unwind the roll without tearing portions of the paper which have adhered to other portions beneath it.

The objects of my invention are to 25 secure an equal and uniform distribution of the wax, reduce the expense of manufacturing wax paper by combining the waxing process with the paper manufacturing process and also to secure a thorough absorption 30 of the wax preparatory to winding the paper upon the receiving roll, thus avoiding adhesion.

In the accompanying drawing which illustrates the practice of my improved process 35 I have shown two drying rolls of a paper manufacturing machine of ordinary type, one of said rolls being shown in side elevation and the other in cross section, and each equipped with apparatus to facilitate the 40 carrying out of my process. My invention is based upon the discovery that by waxing the surface of the drying rolls of a paper making machine the wax can be distributed to the paper uniformly and effectively and 45 the heat of the rolls will dry the paper so that it can absorb the wax and be delivered from the rolls in a condition to be wound upon a receiving roll without sticking, the waxed paper being smooth, dry and hard 50 as it comes from the drying rolls.

In the drawing A and B represent two 55 rotary drying rolls of a paper making machine. These rolls in the machines in ordinary use, are located between the press rolls and the calendering rolls.

d, d' are guide rolls over which a flexible

apron C extends, said apron passing underneath the drying rolls A and B as shown. Other guide rolls e, e' are employed over 60 which the strip of paper F passes, said paper being thus interposed between the apron C and the drying rolls and carried in pressure contact with each of the drying rolls in passing from a roller e to the succeeding roller e'. The drying rolls are filled 65 with steam which is delivered thereto through hollow trunnions G.

By applying a cake of wax to one or all 70 of the drying rolls immediately above the point where such roll receives the strip F 75 of paper the surface of the drying roll may be covered with a thin coating of melted wax which, on coming in contact with the paper, immediately penetrates the latter and distributes throughout the tissue, after 80 which the contact of the drying roll with the paper is sufficiently prolonged to expel any remaining moisture and permit complete absorption of the wax, whereby as the waxed paper leaves the drying roll the 85 paper is firm and the wax hard. By thus simultaneously waxing and drying the paper, I am enabled to utilize the moisture in the paper and the water vapor produced by its evaporation to not only prevent the 90 paper from adhering to the drying roll, but also to facilitate hardening the wax. The wax is not only pressed into the paper and dried, but it is steamed during the initial 95 stages of the process owing to the vapor- 100 ation of the water carried by the paper.

To facilitate applying the wax I employ 105 a pan I upon which the wax may be supported in a position to slide by gravity 95 against the drying roll A. The cake of wax will have a length equal to the strip of paper to be waxed and will therefore coat the entire surface of the drying roll which contacts with such paper. The pan I is preferably hinged at J and is adapted to oscillate between stops K whereby it may be tilted to the position in which one of the 110 pans is shown in dotted lines, when it is not desired to use the wax. I also employ a retaining arm L the extremity of which is 105 elbowed at M in a position to be interposed between the wax and the roll preparatory to tilting the pan to the dotted line position. This arm L will also be supported to bind upon the pivot pin J sufficiently to remain 110 in any position in which it may be adjusted. When the paper is being waxed this retain-

ing arm L will be out of contact with the cake of wax but when it is desired to stop the delivery of wax the arm L will first be swung downwardly until the elbowed extremity M passes between the wax and the drying roll, after which the pan I may be lifted and swung to the dotted line position.

I claim:—

1. That process of making water-proof paper which consists in simultaneously expelling the moisture from newly made paper and impregnating the paper with water-proof material.

2. The process of waxing paper consisting in passing newly made moist paper over a rotating drying roll in pressure contact therewith and simultaneously waxing the

outer surface of said roll prior to the point of contact of the roll with the paper.

3. The process of waxing paper, consisting in applying wax to the paper during the manufacture thereof and during the final drying operation, and simultaneously spreading the wax and compressing the wax and the paper under the influence of heat and for a sufficient period to expel the moisture and simultaneously effect absorption of the wax.

In testimony whereof I affix my signature in the presence of two witnesses.

FRANK H. HOBERG.
